(57) **CLAIM**

The ornamental design for a under hoist support stand, as
shown and described.

DESCRIPTION

FIG. 1 is a front perspective view of the under hoist support
stand as shown in FIG. 1;

FIG. 2 is a front view of the under hoist support stand as
shown in FIG. 1;

FIG. 3 is a rear view of the under hoist support stand as
shown in FIG. 1;

FIG. 4 is a left side view of the under hoist support stand as
shown in FIG. 1;

FIG. 5 is a right side view of the under hoist support stand
as shown in FIG. 1

FIG. 6 is a top view of the under hoist support stand as
shown in FIG. 1; and,

FIG. 7 is a bottom view of the under hoist support stand as
shown in FIG. 1.

The broken lines shown in the FIGS. 1-7 are for the purpose
of illustrating portions of the under hoist support stand
and form no part of the claimed design.
